UNITED STATES PATENT OFFICE.

FREDRICH F. CHOITZ, OF CARNEIRO, KANSAS.

MULTIPLE HORSE HOLDER AND RELEASER.

1,233,551.

Specification of Letters Patent. Patented July 17, 1917.

Application filed May 24, 1916. Serial No. 99,644.

To all whom it may concern:

Be it known that I, FREDRICH F. CHOTZ, a citizen of the United States, residing at Carneiro, in the county of Ellsworth and State of Kansas, have invented certain new and useful Improvements in Multiple Horse Holders and Releasers, of which the following is a specification.

This invention relates to improvements in multiple horse holders and releasers and its object is to provide means whereby a number of animals may be hitched in a stable and simultaneously or individually released as desired. Another object is to produce a device of this class that is simple in construction and operation and cheap to manufacture. With the foregoing and other objects in view the invention consists in the combination and arrangement of parts to be hereinafter fully described in this specification, pointed out in the appended claims and illustrated in the accompanying drawings which form a part of said specification and in which—

25 Figure is a top plan view of my device showing its application in a stable.

Fig. 2 is a front elevation of Fig. 1.

Fig. 3 is a cross section through Fig. 1.

30 Fig. 4 is a view of Fig. 3 with the movable parts in an altered position. Fig. 5 is a section taken on line 5—5 of Fig. 3. Fig. 6 is a top plan view of Fig. 7. Fig. 7 is a section taken on line 7—7 of Fig. 6.

Like reference characters denote corresponding parts throughout the several views.

The reference numeral 1 denotes a stable provided with the partitions 2 that divide it into the stalls 3. The manger wall 4 is provided with the top rail 5 which carries the side rail 6 and to the top rail adjacent the said side rail and within each stall 3 I provide a bracket 7 that pivotally supports a depending post 8 bifurcated as at 9 at its lower extremity for releasable engagement 45 with the crest portion 10 of a beveled lip 11 formed integral with a segmental plate 12 which is connected by a pivot pin 13 to a supporting bracket 14 secured directly to the manger wall 4.

50 A pull rod 15 extends through the several stalls 3, above the brackets 14, through one end of the stable and is connected to a hand

lever 16 located outside the stable and pivoted to a bracket 17 carried by the stable. Within each stall an angular spring arm 18 55 is secured to the pull rod 15 with one end disposed in a depression in the plate 12. In Fig. 3 of the drawings the device is shown in operative position. The bifurcated end of the post 8 is in engagement with the crest 60 of the lip 11, the hitching ring 19 having been placed about the post 8 previous to its specified engagement. To release one animal at a time one arm 18 is manually raised out of its frictional engagement with its plate 12 and 65 that plate moved upon its pivot 13 until the beveled lip 11 passes out of engagement with the post 8; the ring 19 may now be removed thus freeing the animal. To release all of the animals simultaneously the operator 70 from outside the stable moves the pull rod in a manner to cause the several arms 18 to move their plates 12 into a position to disengage the lips 11 from the posts 8 thus 75 freeing the several hitching rings 19 and freeing the animals. The device is re-set by placing the arms 18 individually into engagement again with their respective plates 12.

What is claimed is:—

1. In a multiple horse holder and releaser, a pull rod, pivotal plates disposed in a plane below the horizontal plane of said pull rod, integral beveled lips formed upon said plates, pivotally suspended posts normally 85 engaging the said beveled lips and means connecting said pull rod and said pivotal plates whereby movement of the former may be transmitted to the latter.

2. In a multiple horse holder and releaser, 90 a pull rod, pivotal plates disposed in a plane below the horizontal plane of said pull rod, integral beveled lips formed upon said plates, pivotally suspended posts having their lower ends bifurcated for normal engagement with the crest of the said beveled lips and means connecting said pull rod and pivotal plates whereby movement of the former may be transmitted to the latter.

3. In a multiple horse holder and releaser, 100 a pull rod, pivotal plates disposed in a plane below the horizontal plane of said pull rod, integral beveled lips formed upon said plates, pivotally suspended posts having

their lower ends bifurcated for normal engagement with the crest of the said beveled lips and angular arms carried by said pull rod and normally engaging said pivotal plates.

In testimony that I claim the foregoing as my own I have hereto affixed my signa-

ture in the presence of two subscribing witnesses.

FREDRICH F. CHOITZ.
